CLAIM

The ornamental design for a lamp post, substantially as
shown and described.

DESCRIPTION

FIG. 1 is a right side view of one embodiment of the
lamp post of this invention;

FIG. 2 is a bottom view of the lamp post of FIG. 1;

FIG. 3 is a top view of the lamp post of FIG. 1;

FIG. 4 is a right side view of a second embodiment of
the lamp post of this invention;

FIG. 5 is a bottom view of the lamp post of FIG. 4; and

FIG. 6 is a top view of the lamp post of FIG. 4.

*FIG. 1**FIG. 2**FIG. 3*

FIG. 4

FIG. 5

FIG. 6
